UNITED STATES PATENT OFFICE.

PHILIP DIEHL, OF ELIZABETH, NEW JERSEY, ASSIGNOR TO THE SINGER
MANUFACTURING COMPANY, A CORPORATION OF NEW JERSEY.

SEWING-MACHINE-ATTACHMENT DRAWER.

SPECIFICATION forming part of Letters Patent No. 716,004, dated December 16, 1902.

Application filed March 31, 1902. Serial No. 100,773. (No model.)

To all whom it may concern:

Be it known that I, PHILIP DIEHL, a citizen of the United States, residing at Elizabeth, in the county of Union and State of New Jersey, have invented certain new and useful Improvements in Sewing-Machine-Attachment Drawers, of which the following is a specification, reference being had therein to the accompanying drawings.

10 This invention has for its object to provide a compartment-receptacle for sewing-machine attachments, which receptacle is made in the form of a drawer for a sewing-machine stand or table, preferably the shallow middle drawer of a sewing-machine stand or table. The attachments to be contained in the receptacle are of various shapes and sizes, and, in order that a receptacle in which these attachments of various shapes and sizes will 15 properly fit, it is necessary that the various compartments to contain the same should each be approximately of a shape and size of the article to be placed therein. Furthermore, it is desirable that the attachment-receptacle should be produced cheaply.

In carrying my invention into effect I form comparatively shallow compartments or recesses in one face of a wooden block by subjecting the block to pressure under a die having relief or projecting portions of the shapes and sizes of the various comparatively shallow compartments or indentations to be formed, and I form relatively deep compartments by cutting away parts of the edges of the block and then inclosing the cut-away parts or edges by sides forming a part of the drawer in which the compartment-block is placed and of which it forms a part, the drawer being provided with a bottom and 30 with suitable guiding-slides to fit in the sewing-machine stand or table after the compartment-block has been suitably secured in the drawer of which it forms a part, the exposed inner surfaces of the drawer being preferably 35 covered by a fibrous flock attached to said surfaces by a coating of a suitable adhesive applied in liquid form and to which adhesive coating when the latter is partly dry the flock is applied.

40 In the accompanying drawings, Figure 1 is a plan view of a compartment-drawer con-

structed in accordance with the invention and filled with a set of sewing-machine attachments; and Fig. 2 is a cross-section of the same on the same on line 2 2, Fig. 1, with 55 the attachments omitted.

Referring to the drawings, 11 denotes a block, preferably of soft wood, and in the upper face of which relatively shallow compartments 12 are formed, preferably by subjecting the block to pressure under a die having relief or projecting portions of the shapes and sizes of the various shallow compartments or indentations to be formed. Each of these various relatively shallow compartments 12 is of approximately the shape or size of the relatively thin sewing-machine attachment 13 to be placed therein, while for providing receptacles for the larger or thicker attachments 14 the block is cut away at portions of its edges to form relatively deep compartments 15. The drawer is provided with the front face 16 and with a rear side portion 17, each extending as a projecting ledge above the upper unindented surface of the block 75 11 and also extending around the relatively deep compartment or compartments 15 to form an inclosing side or boundary for the latter. The drawer is also provided with guiding-slides 18, which will steady the attachment-drawer in the sewing-machine stand or table, the said slides 18 forming practically the ends of the drawer and extending, as ledges, above the upper unindented face of the block 11 at the ends thereof. 85

When the attachment-drawer, with its various shallow and deep compartments, has been constructed in the manner indicated and has been provided with a bottom 20, beneath the block 11, a suitable finish is given to the exposed inner surfaces of the drawer by first covering such surfaces with a suitable liquid adhesive material (preferably a thin varnish) and then when such adhesive material is partly dried applying a fibrous flock thereto. When the adhesive material is fully dried, the loose or unattached flock is brushed off, leaving a flock-covered surface or coating 19, which presents the appearance of felt or cloth and gives the effect of a felt 95 or cloth lining.

Having thus described my invention, I

claim and desire to secure by Letters Patent—

1. The herein-described sewing-machine-attachment drawer, consisting of a block provided in its upper face with relatively shallow compartments, and having portions of its edges cut away or omitted to form one or more relatively deep compartments at the edge or edges of said block, a front face and a rear side portion for said drawer between which said block is fitted, and which rear side portion partly forms the said deep compartment or compartments, and backwardly-projecting slides forming the ends of the drawer; said front face, rear side portion and end slides projecting above the upper unindented face of the said block, to form an inclosing receptacle.

2. A sewing-machine-attachment drawer consisting of the block 11, having shallow 20 compartments in its upper face, and one or more deep compartments or recesses at its edge or edges, the front face 16, the rear portion 17 and the rearwardly-extending end slides 18 all projecting above the upper unindented surface of said block, the exposed inner surface of the said drawer having a flock-formed lining 19, and the said drawer having a bottom 20 beneath the said block 11.

In testimony whereof I affix my signature 30 in presence of two witnesses.

PHILIP DIEHL.
